PROCESS OF DISTILLING TAR AND RE-COVERING OILS WITH APPARATUS THEREFOR

Stuart Parmelee Miller, Englewood, N. J., assignor to The Barrett Company, New York, N. Y., a corporation of New Jersey

Application August 31, 1929. Serial No. 389,644

13 Claims. (Cl. 202—30)

This invention relates to the distillation of tar in hot gases, for example, hot coke oven gases or other hot coal distillation or gasification gases to produce a high melting point pitch with rectification of the resulting distillate vapors.

When tar is distilled to produce a high melting point pitch, i. e., a pitch with a melting point of 300° F. or 400° F. or higher, and the distillation is carried out under conditions which tend to prevent decomposition of the tar constituents, the distillate obtained will contain higher boiling constituents which are solid or semi-solid in an isolated state at ordinary temperatures.

It is an object of this invention to provide for the distillation of tar in hot gases and the recovery of a condensate including oils of high boiling range but free from such higher boiling solid or semi-solid constituents and also for the recovery of a fraction of higher boiling range containing a high percentage of such constituents. Where a fraction of the higher boiling range rich in such constituents is desired, the high boiling fraction recovered by the rectification process of this invention may be collected separately as a separate product of the operation. Where oils free from such higher boiling constituents are desired, the fraction containing such higher boiling constituents removed from the distillate may be separately collected or it may be returned to the still to be subjected to redistillation, or it may be returned to the still and be drawn off with the pitch produced therein.

It is an object of the invention to provide for the return of a fraction of higher boiling constituents recovered from the gases and vapors resulting from the distillation of tar with hot gases, to the still, either to subject that fraction of the condensate to redistillation or to blend it with the pitch produced in the still to form a composite pitch product within the still.

According to the present invention, tar is distilled to pitch by direct and intimate contact with hot gases such as hot coke oven gases in the form of a fine spray, and where the gases employed for the distillation are pitch-laden gases, i. e., gases such as coke oven gases which contain pitchy constituents in suspended form, the tar is sprayed into the gases in the form of an intense spray which not only effects distillation of the tar but simultaneously detars the gases. The gases and vapors resulting from this formation of pitch are passed thru a rectifying column and then cooled and where desired, fractional cooling of the gases may be employed to produce

two or more oil fractions. Condensate from this cooling of the gases is advantageously employed as the rectifying medium and where two or more distillate fractions are recovered from the gases leaving the rectifying column, distillate of the highest boiling range is employed to advantage as the rectifying medium. The rectification is so controlled as to fractionally condense in the rectifying column vapors of a particular boiling range and to remove them as liquids from the base of the fractionating column. In removing in the rectifying column constituents which are semi-solid or solid in an isolated state, precautions should be taken to insure that the fraction removed from the bottom of the rectifying column is maintained in a liquid state, and not allowed to solidify in the draw-off. This is done preferably by maintaining the draw-off from the rectifying column at a sufficiently high temperature to keep the condensate liquid. According to this invention the rectification and subsequent cooling of the gases is controlled to remove constituents of a desired boiling range in the rectifying column and on subsequent cooling of the resulting gases and vapors to yield a distillate fraction or fractions free or relatively free from constituents of this boiling range.

When, for example, it is desired to collect as a separate fraction the high boiling solid or semi-solid resinous or greasy constituents which are volatilized from tar in the production of a high melting point pitch, these higher boiling resinous or greasy constituents are removed from the gases in a rectifying column before the gases are cooled for the recovery of other fractions of condensate and the oil vapors passing from the rectifying column with the hot gases will be relatively free from vapors of these higher boiling constituents. On cooling, oils substantially free from these higher boiling constituents will be obtained, and they can be recovered as one oil or by a stepwise cooling can be recovered as several oil cuts, for example, as creosote oil and tar acid oil.

The degree of distillation of the tar, the amount and characteristic of the reflux supplied to the rectifying column and other factors commonly known to those skilled in the art may be regulated to produce a high yield of oils including oils of higher boiling range, but free or substantially free from these solid or semi-solid constituents, as desired. Either oils free from the higher boiling constituents or the higher boiling constituents which are solid or semi-solid in an isolated state at ordinary temperatures may readily be col-

lected, according to the process of this invention. According to a preferred method of carrying out the invention, the distillation of the tar is effected at a coal distillation or other coal gasification plant and the heat of the hot coal gasification gases is employed for effecting the distillation. The gases are used at substantially the temperature at which they leave the ovens or retorts, while they contain substantially their original vapor content and at a temperature such that after being brought into direct contact with the tar in the still and supplying the heat necessary for the distillation of this tar they leave the still at a sufficiently high temperature to carry in vapor form at least some of these higher boiling constituents which are solid or semi-solid in an isolated state at ordinary temperatures. The distillation in the still is effected in such a manner that the gases leaving the still contain such higher boiling constituents and in such a way that these constituents are not decomposed in the still. To accomplish this, the tar is brought into direct and intimate contact with the gases in the still, preferably in the form of a fine intense spray in which state the tar is subjected to the action of the hot gases for only a relatively short period of time and the gases are rapidly cooled and the tar is rapidly vaporized so that the pitch residue remaining from the distillation is rapidly brought into equilibrium with the partially cooled gases. The distillation may be carried to the point where a pitch with a melting point of 300° F. or 400° F. or higher is produced and the gases may leave the still at a temperature of 325° C. or higher. After leaving the still the gases and vapors pass up thru a rectifying column, which may, for example, be of the ordinary packed type, and then to condensers. Any suitable oil may be employed for the rectification. Preferably oil condensed from the gases after they leave the rectifying column is returned to the rectifying column to effect the rectification.

The lower boiling constituents of the oil sprayed into the rectifying column are vaporized and higher boiling constituents present in the gases are simultaneously condensed and separated from the gases. The rectification separates the higher boiling constituents from the vapors of lower boiling oils which pass over from the rectifying column into the condensers. These higher boiling constituents may be separately collected as a separate high boiling fraction or they may be returned to the still and be subjected to redistillation therein, or they may be blended with the pitch produced in the still, or they may be used in any desired way.

In order to produce a high melting point pitch, i. e., a pitch with a melting point of about 300° F. or 400° F. or higher, by contacting tar with hot gases, the hot gases and tar are advantageously passed thru the still in a concurrent direction so that the incoming tar is brought into direct and intimate contact with the hottest gases and the pitch immediately before being withdrawn from the still is sprayed into the somewhat cool and partially saturated gases. Tar may be distilled to a high melting point pitch in this manner without objectionable coking of the pitch. The distillation may be carried on in two stages. In the first stage of the distillation tar is brought into direct contact with the hot gases and vapors from the second stage of the distillation and a semi-pitch is produced. During this stage of the distillation partially saturated gases of a relatively low temperature are employed for the distillation

and the tar and gases advantageously flow in countercurrent direction. In the second stage of the distillation semi-pitch from the first stage is distilled to pitch of a high melting point. The semi-pitch in the form of an intense spray is sprayed into the fresh hot gases and distilled therein. In this stage of the distillation the hot gases and the semi-pitch are advantageously passed thru the still in a concurrent direction. The semi-pitch is sprayed and resprayed into the gases. The high melting point pitch produced is withdrawn from the still at the end of the still at which the gases and vapors pass from the second stage of the distillation to the first stage of the distillation. It is to be understood that the invention is not limited to this method of distillation or to distillation in this type of still, but that other stills and other distillation processes may be employed.

When the high boiling constituents from the rectifying column are added to the still to be blended with the pitch and to be drawn off from the still blended therewith as a composite blended product, these constituents are advantageously added to the still at or near the point where the pitch is drawn off from the still. Where these constituents are returned to the still for redistillation they are advantageously added to the still at a point remote from that at which the pitch is drawn off of the still and may advantageously be added to the still at the same point as the tar, or as the semi-pitch when two-stage distillation is employed.

Where coke oven gases or other pitch-laden gases are employed for the distillation, the tar is sprayed into the gases in the still in the form of such a fine intense spray that the gases are scrubbed and detarred simultaneously with the distillation of the tar, and the pitch thus removed from the gases is combined with the pitch residue from the distillation to give the high melting point pitch product of the process. The condensate recovered from the gases leaving the still is a clean condensate, so that both the higher boiling fraction separated from the gases in the rectifying column and the oils subsequently recovered from the gases are free or substantially free from tarry or pitchy constituents.

In the drawings, one arrangement of a still in connection with a coke oven battery and means for rectifying the distillate is shown in more or less detail. The drawings also include a schematic showing of this arrangement and modified arrangements for accomplishing rectification according to other processes embraced by this invention. It is to be understood that the drawings illustrate the invention but that the invention is not limited thereto. In the drawings—

Fig. 1 is a plan view of a coke oven plant equipped for carrying out the invention;

Fig. 2 shows an elevation of the apparatus of Fig. 1;

Fig. 3 is a section thru the still on the line 3—3 of Fig. 2;

Fig. 4 is a schematic showing of the apparatus shown in greater detail in Figs. 1-3; and

Figs. 5-9 are similar schematic drawings of modified adaptations of the invention.

In Fig. 1, 5 indicates a coke oven battery, the ovens of which are connected with the collector main 6 thru uptake pipes and goose necks 7. A cross-over main 8 connects the collector main with condensers, etc., (not shown). This apparatus is of the usual type and is shown more or less diagrammatically in Fig. 1.

- At the rear of the ovens is a still 10. The hot coke oven gases from selected ovens of the battery pass up thru uptake pipes and goose necks 11 and thru the hot gas header 12 into this still 10. By the proper manipulation of valves in the uptake pipes 11 and the uptake pipes 7, gases from the selected ovens may be passed either to the collector main 6 or thru the hot gas header 12 into the still 10. From the still the gases pass 10 thru the hot gas saturator 11' up thru the opening 12' into the rectifying column 13. The uptake pipes 11, the hot gas header 12, the still 10 and the saturator and rectifier 11' and 13 are advantageously insulated as at 40 to prevent loss 15 of heat by radiation.

The tar to be distilled is sprayed into the hot gas saturator thru the nozzle 14. It passes down over the baffle 15 to the bottom of the saturator where the partially distilled tar is collected and 20 drawn off thru the line 16 and fed into the end of the still at which the hot gases enter. In the still is a roll 17 partly immersed in the tar and pitch in the still and adapted to be rotated at high speed, for example, 900-1200 R. P. M. by the 25 motor 18. This roll sprays the partially distilled tar or pitch up into the hot gases as an intense spray; distillation is effected by the hot gases and the hot gases are scrubbed and substantially detarred. The partially distilled tar is distilled to 30 pitch which is withdrawn thru the coke trap 19 by the levelling arm 20. The position of the levelling arm controls the depth to which tar and pitch are allowed to accumulate within the still 10 and this in turn determines the nature of the 35 spray thrown by the roll 17. The high melting point pitch produced in the still may be drawn off into the trough 21 and there suddenly chilled and granulated by a stream of cold water from the line 22. The pitch thus chilled may be collected in any suitable storage bin 23.

When pitch of a high melting point, for example, pitch with a melting point of 300° or 400° F. or higher is produced, the gases passing from the still are enriched not only in lower 45 boiling constituents but also in vapors of higher boiling resinous or greasy compounds which are solid or semi-solid in an isolated state. According to this invention these higher boiling constituents and oils substantially free from such 50 constituents are collected as separate products.

The hot enriched gases pass from the still 10 up thru the hot gas saturator 11' where they are sprayed with tar; and the tar is partially distilled and the gases are further saturated in lower boiling constituents. The gases are then 55 passed to the rectifier 13. From the rectifier the gases pass to condensers 25 and 26, which may be either direct or indirect condensers. The relatively heavier oils separated in the condenser 60 25 are collected in the tank 27 and the lighter oils separated in the condenser 26 are collected in the storage tank 28.

Higher boiling oils from this storage tank 27 are returned in whole or in part, depending on the nature of the tar distilled, the fractions desired, etc. to the rectifying column by the pump 29 thru the line 30. The condenser may be so located as to allow the oils to run by gravity to the rectifying column. The oils are sprayed into the gases in the rectifier thru the spray nozzle 31. Lower boiling constituents of these oils are volatilized and carried over by the gases from the rectifier into the condenser 25. Resinous and greasy constituents or other unde-

sirable condensate of high boiling range present in these higher boiling oils will to a large extent be separated out as liquids in the rectifier 13. The unvolatilized oils together with any condensate formed from the vapors in the gases 80 flow down over the baffling means 32 in the rectifying column and are drawn off at 33. This high boiling fraction may be separately collected in the storage tank 34.

Instead of one condenser at 26, fractional condensers may be employed. By proper control of the amount, temperature and character of the oil returned to the rectifying column, the degrees of fractionation of the oil may be determined and the character of the oils drawn off from the rectifier, from the partial condenser and from the total condenser or condensers may be regulated.

In order to produce creosote oil low in constituents which are solid or semi-solid in an isolated state at ordinary temperatures, the operation is so controlled that higher boiling resinous or greasy constituents are condensed from the gases in the rectifier 13. When all the oils from the condenser 25 and tank 27 100 are refluxed in the rectifying column, the oils condensed in the cooler 26 and collected in the storage tank 28 will be free or substantially free from higher boiling solid or semi-solid constituents. This oil from the tank 28 may be used 105 alone as creosote oil or where only a portion of the oil from the tank 27 has been refluxed thru the rectifying column, the oil from the tank 28 may be blended with a portion of the fraction condensed in the cooler 25 and collected in the 110 tank 27 for creosote oil. Either oil may be blended with coal tar to produce so-called coal tar solution.

The products of the operation are a high melting point pitch collected in the bin 23, the 115 oil free from higher boiling resinous or greasy constituents collected in 28, the fraction rich in these higher boiling constituents which is collected in 34, and if desired, an intermediate oil from the tank 27. A portion of the oil from 120 this tank 27 may be drawn off as a separate product or a portion may be blended with the oil collected in the tank 28, the balance being pumped to the rectifying column 13.

This apparatus shown in more or less detail 125 in Figs. 1-3 is shown schematically in Fig. 4. The coke oven battery is not shown in this figure. The still is indicated at S. The saturator 11' is indicated at T. The rectifier 13 is shown at R. The condensers 25 and 26 are shown at C1 130 and C2. The pitch draw-off and tar feed are indicated by the legends. This showing is schematic and Figs. 5-9 are similarly schematic and indicate various modifications of the apparatus here shown.

Fig. 5 shows a slight modification of the arrangement shown in Fig. 4 in which the high boiling fraction separated in the rectifying column R is returned to the still together with the semi-pitch from the saturator T to subject 140 it to redistillation.

Fig. 6 illustrates a still with tar fed to the still thru a saturator T and rectification of oils with a single condenser C. Only a portion of the oils recovered in the condenser are sprayed 145 into the rectifying column. The balance is drawn off as a separate product relatively low in higher boiling constituents.

Fig. 7 is quite similar to Fig. 4 but the rectifying column R is shown as a separate unit in 150

stead of being combined with the saturator T in a single column. The same processes can be carried out in the arrangement shown in Fig. 7 as can be carried out in the arrangement 5 shown in Fig. 4.

- Fig. 8 shows a modification in which the gases and vapors from the still pass directly to the rectifying column R where they are sprayed with distillate which separates in the condenser C1. 10 The high boiling fraction removed in the rectifying column may be separately collected or put to any desired use.

Fig. 9 is still another modification of Fig. 4 in which the high boiling fraction from the rectifying column R is blended with the pitch in the still to produce a composite pitch product. This high boiling fraction is returned to the still at the end adjacent to the pitch draw-off. High boiling constituents thus returned to the still may 20 be subjected to partial redistillation, but to large extent they will be removed from the still blended with the pitch before they are revolatilized. Instead of blending the high boiling fraction with the pitch in the still, the blending may be effected outside of the still after the pitch has been 25 drawn off from the still.

I claim:

1. The method of distilling tar and recovering high boiling resinous or greasy constituents, 30 which comprises bringing coal tar into direct contact with hot coal gasification gases whereby the tar is distilled to pitch of a high melting point and resinous or greasy constituents are volatilized from the tar, bringing the gases and 35 vapors resulting from the distillation into direct contact with a regulated quantity of oil to effect only partial cooling of the gases and vapors whereby resinous and greasy constituents are condensed and separated from the gases and remaining vapors, and subsequently cooling the resulting gases and vapors to separate oils therefrom.

2. The method of distilling tar and rectifying the distillate therefrom, which comprises bringing coal tar into direct contact with hot coal gasification gases, whereby the tar is distilled and pitch of a high melting point is produced, passing the resulting gases and vapors thru a rectifying tower and then cooling the resulting gases 50 and vapors to condense oil and passing oil thus recovered in a countercurrent direction and in direct contact with the gases and vapors passing thru the rectifying column, whereby high boiling resinous and greasy constituents are condensed 55 and separated from the gases and remaining vapors in the rectifying column.

3. The method of distilling tar and rectifying the distillate therefrom which comprises bringing coal tar into direct and intimate contact with 60 hot gas in a still whereby the tar is distilled to pitch, passing the resulting gases and vapors thru a rectifying column and cooling them therein by bringing them into direct contact with oil condensate of successively increasing volatility therein, returning condensate obtained in the rectifying column to the still, and cooling the gases and vapors leaving the rectifying column to recover oil condensates therefrom.

4. The method of distilling tar and rectifying 70 the distillate, whereby oils, including oils of higher boiling range, substantially free from higher boiling resinous or greasy constituents are produced, which comprises bringing coal tar into direct contact with hot coal gasification gases, 75 whereby the tar is distilled and pitch of a high

melting point is produced, passing the resulting gases and vapors thru a rectifying column and then thru a fractional condensing system where various oil fractions are separated from the gases and employing the highest boiling oil fraction as 80 rectifying liquid in the rectifying column to separate high boiling resinous or greasy constituents from the gases and remaining vapors in the rectifying column while allowing higher boiling oils to pass over from the rectifying column into the 85 condensing system.

5. The method of distilling tar, which comprises collecting the gases from a plurality of the ovens or retorts of the coal distillation plant, bringing them into direct contact with coal tar in a still, whereby the tar is distilled and pitch is produced, passing the resulting gases and vapors thru a rectifying column, and then thru a condensing system, bringing oil condensates into direct contact with the gases and vapors in the rectifying column in such a manner as to cool the gases therein and subject the gases to contact with condensates of successively increasing volatility to separate higher boiling constituents therein, and returning the higher boiling constituents to the still and blending them with the pitch therein.

6. The method of distilling tar, which comprises collecting the gases from a plurality of the ovens or retorts of the coal distillation plant, 105 bringing them into direct contact with coal tar in a still, whereby the tar is distilled and pitch is produced, passing the resulting gases and vapors thru a rectifying column in a generally countercurrent direction and in direct contact 110 with oil condensates so as to only partially cool the gases and separate higher boiling constituents therefrom, returning the higher boiling constituents to the still and subjecting them to redistillation therein, and cooling the rectified gases and 115 vapors to recover the oil condensates therefrom.

7. The method of distilling tar and rectifying the distillate therefrom, which comprises bringing coal tar into direct contact with hot coal gasification gases, whereby the tar is distilled 120 and pitch is produced therefrom, bringing the resulting gases and vapors into contact with further tar and distilling it, passing the resulting gases and vapors thru a rectifying column in a generally countercurrent direction to and in 125 direct contact with oil condensates so as to only partially cool the gases and separate higher boiling constituents therefrom, and thereafter cooling the rectified gases and vapors to separate the oil condensates therefrom.

8. The method of distilling tar and rectifying the distillate therefrom, which comprises distilling coal tar in two stages by spraying semi-pitch into direct contact with fresh hot coal distillation gases, passing the semi-pitch and the hot 130 gases thru a still in a concurrent direction while spraying the semi-pitch into the gases in the form of a fine intense spray, whereby the semi-pitch is distilled to pitch of a high melting point, and then bringing the resulting gases and vapors 135 into direct contact with tar and thereby distilling the tar to produce the semi-pitch, passing the resulting gases and vapors thru a rectifying column in a generally countercurrent direction and in direct contact with oil condensates so as to only partially cool the gases and separate higher boiling constituents therefrom, and cooling the rectified gases and vapors to recover the oil condensates.

9. The method of distilling tar and rectifying 140

- the distillate therefrom, which comprises bringing the tar into direct contact with hot coal distillation gases whereby the tar is distilled to pitch having a melting point of at least 300° F., passing the resulting gases and vapors up thru a rectifying column, withdrawing them from the rectifying column and cooling them to recover oil condensates, spraying the oil condensates into the top of the rectifying column in such a manner that the oil passes downwardly in the rectifying column in a generally countercurrent direction and in direct contact with the gases and vapors passing up therethru, thereby partly cooling the gases and separating high boiling greasy and resinous constituents therefrom, and withdrawing such constituents from the bottom of the rectifying column. 80
10. In combination with a coal distillation plant a still, a hot gas saturator, a rectifying column, a condenser, means for passing hot coal distillation gases from ovens or retorts of the plant to the still, means for passing hot gases and vapors from the still to the saturator, means for bringing tar into direct contact with the hot gases and vapors in the saturator, means for passing hot gases and vapors from the saturator to the rectifying column, means for withdrawing liquid at the base of the rectifying column, means for withdrawing gases from the rectifying column and conveying them to the condenser. 85
11. In combination with a coal distillation plant, a still, a pitch draw-off from the still, means for maintaining a small reservoir of liquid in the still, a roll for spraying the liquid into gases passing thru the still, means for passing hot coal distillation gases from a plurality of the ovens or retorts of the coal distillation plant into the still, a hot gas saturator, means for conveying tar to the saturator and residue from the saturator to the still, a rectifying column, a condensing system, means for passing hot gases and vapors from the still to the saturator and then to the rectifying column and then to the condensing system, and means for supplying condensate from the condensing system to the rectifying column. 90
12. The method of distilling tar and rectifying the distillate therefrom which comprises bringing coal tar into contact with hot coal distillation gases in the form of a fine intense spray, whereby the tar is distilled to pitch and the gases are simultaneously cleaned and then rectifying the resulting clean gases to separate higher boiling oils from vapors of lower boiling oils said rectification being effected by bringing oil condensate into direct contact with the gases and vapors in the rectifying column in such a manner as to cool the gases therein and subject the gases to contact with condensate of successively increasing volatility. 95
13. The method of simultaneously producing high melting point pitch and creosote oil free from high boiling greasy and resinous constituents, which comprises distilling tar to pitch of high melting point by bringing the tar into direct and intimate contact with hot coal gasification gases whereby high boiling greasy and resinous constituents are distilled off by the hot gases, removing the high boiling greasy and resinous constituents from the hot gases and vapors, and then cooling the remaining hot gases and vapors to condense a creosote oil substantially free from the high boiling greasy and resinous constituents. 100
14. The method of simultaneously producing high melting point pitch and creosote oil free from high boiling greasy and resinous constituents, which comprises distilling tar to pitch of high melting point by bringing the tar into direct and intimate contact with hot coal gasification gases whereby high boiling greasy and resinous constituents are distilled off by the hot gases, removing the high boiling greasy and resinous constituents from the hot gases and vapors, and then cooling the remaining hot gases and vapors to condense a creosote oil substantially free from the high boiling greasy and resinous constituents. 110
